UNITED STATES PATENT OFFICE

104,624

DESIGN FOR A FEED TROUGH

Albert N. Eaton, Omaha, Nebr.

Application March 27, 1937, Serial No. 68,432

Term of patent 14 years

To all whom it may concern:

Be it known that I, Albert N. Eaton, a citizen of the United States, residing at the city of Omaha, in the county of Douglas and State of Nebraska, have invented a new, original, and ornamental Design for a Feed Trough, of which the following is a specification, reference being had to the accompanying drawing forming a part thereof.

In the drawing Figure 1 is a top plan view of

a feed trough, and Figure 2 is an end view of the same.

Figure 3 is a view in side elevation of the feed trough, and Figure 4 is a view of the feed trough in longitudinal section.

I claim:

The ornamental design for a feed trough, as shown.

ALBERT N. EATON.
